UNITED STATES PATENT OFFICE.

ROBERT D. DUNCAN, JR., OF EAST ORANGE, NEW JERSEY, ASSIGNOR TO WIRED RADIO, INC., OF NEW YORK, N. Y., A CORPORATION OF DELAWARE.

WIRED RADIO ON POWER LINES.

Application filed March 12, 1925. Serial No. 14,856.

This invention has to do with the transmission of high frequency carrier current for signaling purposes over electric power lines—especially wired radio broadcasting—5 and has for its object to modify the characteristics, at high frequencies, of power distribution transformers which, under some conditions, are found to be deficient in their ability to transmit high frequency currents, 10 and thereby to obtain more uniform distribution of the carrier current through the entire power network.

Experience has shown that in electric power distribution systems, on which high 15 frequency currents are superimposed as in wired radio broadcasting, that as between subscribers about equally distant from the central power station, at which the carrier current is impressed on the system, there is 20 often a large difference in the strength of signals received. This condition has been found to be due, in some cases, to the fact that certain power transformers, not being 25 designed with a view to passing high frequencies, have such high input impedance as viewed from the transmission line that very little high frequency current can pass through the turns of the primary windings, and, accordingly, there is failure to induce 30 sufficient high frequency current into the secondary windings. This condition may be cured by the use of high frequency by-passing 35 circuits between the primary and secondary windings but to do so it is necessary to employ expensive condensers, properly housed and mounted. Ordinarily two condensers would be required for each transformer if by-passing circuits were to be employed.

40 The present invention provides a different solution of the problem—avoiding the necessity for the use of by-pass condensers; greatly reduces the cost which would be involved in the use of by-pass condensers; and 45 is found to be a marked improvement from the standpoint of efficiency.

The practise of this invention consists in the addition of auxiliary inductance in series with the primary or input winding of a 50 transformer. The value of the auxiliary inductance is preferably so chosen that the effective overall reactance at the high fre-

quency dealt with, of the combined primary winding and auxiliary inductance, is either substantially zero or is reduced to any desired extent depending upon the necessities of each particular case. By reason of the tuning or partial tuning thus capable of being effected, relatively large high frequency currents can be caused to flow through the 55 primary winding of the power transformer, thereby causing a proportionate increase of high frequency current in the turns of the secondary winding and hence to the wired radio receiving apparatus of the subscriber 60 or subscribers.

Because of the relative newness of wired radio operation over electric lighting systems, with the consequent absence of comprehensive experimental data, the high frequency deficiencies of various types and sizes of distribution transformers have had to be determined by actual receiving tests at subscribers' stations served by different transformers. Having thus determined the existence 70 of deficiencies, a subsequent study and determination of the high frequency characteristics of the transformers has disclosed the reasons for such deficiencies and yielded the present method of correcting therefor. 75

For a more comprehensive explanation and description of the invention reference will now be had to the accompanying drawing, in which,

Fig. 1 is a diagrammatic illustration of 80 a power transmission line having a transformer bridged across it and on which it is assumed there is superimposed a high frequency carrier current.

Figs. 2, 3 and 4 are reactance and resistance curves,

Fig. 5 is an equivalent circuit diagram 85 illustrating the character of the high frequency impedance of the primary winding of the transformer of Fig. 1.

Fig. 6 is a circuit diagram of a power line and transformer like that of Fig. 1 but including an auxiliary inductance in series with the primary winding of the transformer, and,

Fig. 7 is a circuit diagram illustrating the 90 equivalent impedances of the primary winding of the transformer and auxiliary inductance of Fig. 6.

In Fig. 1, 1 and 2 are the two conductors, respectively, of a power transmission line carrying low frequency power current generally at a relatively high voltage and high frequency signaling current or carrier current. 3 is the primary winding of a power transformer 4, and is bridged across the line. The secondary winding 5 is connected to local distribution lines 6, 7 and 8 and at its mid point is usually grounded as indicated at 9. Across the lines 6, 7 and 8 are shown lamps or other power consuming devices 10 and wired radio receiving apparatus 11.

The high frequency current I , which will flow through the primary winding 3, due to the high frequency voltage E , across the terminals of the primary winding is given by

$$(1) \quad I = \frac{E}{Z}$$

where Z is the input impedance of the transformer effective at the particular high frequency dealt with. The lower the value of Z , the greater that of I , for a constant E .

Impedance Z is made up of two components, resistance and reactance. By actual experiment it has been determined that the reactance of a transformer as viewed from the high voltage winding varies with the frequency in the manner shown by curve 12 in Fig. 2. It is seen that at zero frequency or direct current the reactance is zero; at low frequencies a relatively low positive value, that is, inductive reactance predominates—increasing with increase of frequency to a positive maximum value, and drops through zero to a maximum negative value, that is, capacitive reactance which with further increase of frequency approaches zero asymptotically.

The frequency f_0 may be of the order of several thousand cycles, its exact value depending upon the size of the transformer, its loading and other factors.

The resistance component of the impedance as a function of the frequency is given by curve 13 of Fig. 3 and, as indicated, is always positive—attaining a high value at f_0 .

At any frequency f , the impedance, is expressed by

$$(2) \quad Z = \sqrt{r^2 + (-x')^2}$$

and since x' is negative, that is, capacitive,

$$(3) \quad -x' = -\frac{1}{2\pi f C}$$

in which f is the frequency and C the winding capacity.

Viewed from the standpoint of lines 1, 2, transformer 4, at the frequency f has the characteristics of and may be represented by a circuit composed of a resistance in series with a capacity as shown in Fig. 5. The current traversing the circuit is given by equation (1).

As an example of the values of r , x' and Z

ordinarily dealt with: in a certain one kilowatt transformer, at a frequency of 40,000 cycles

$$r = 7,000 \text{ ohms}; \quad x' = 53,000 \text{ ohms}; \quad Z = 53,500 \text{ ohms.}$$

From Equation (1) it is obvious that an increase in current I may be had by a decrease in the value of Z . With a constant frequency, the impedance Z may be decreased by decreasing either of its components r or x' . The latter offers the most immediate possibilities. By adding, in series with the primary winding 3, an auxiliary inductance as shown in Fig. 6, the capacitive reactance is either wholly or in part offset. In Fig. 6 the auxiliary inductance is represented by reference numeral 16.

The manner of obtaining a reduction in the capacitive reactance is illustrated by curves 12 and 14 of Fig. 2 and curve 15 of Fig. 4. The reactance of a pure inductance is given by

$$(4) \quad x'' = 2\pi f L$$

where f is the frequency and L the inductance. This is the equation of a straight line with x'' and f as the variables and is represented by curve 14 of Fig. 2. The effective reactance of the circuit 16, 3 of Fig. 6 is the algebraic sum of the ordinates of curves 12 and 14 which yield curve 15 of Fig. 4. Then in Fig. 4,

$$(5) \quad x''' = x'' - x'$$

Obviously if $x'' = x'$,
 $x''' = 0$

Again, viewed from the standpoint of lines 1, 2, the circuit of Fig. 6 has the characteristics of and may be represented by the equivalent circuit of Fig. 7. The impedance of this circuit is

$$Z = \sqrt{r^2 + (x'' - x')^2}$$

$$= \sqrt{r^2 + \left(2\pi f L - \frac{1}{2\pi f C}\right)^2}$$

Utilizing the values previously given wherein $x' = 53,000$ ohms and assuming that it is desired to reduce this by 50%, it is obvious that $x'' = 26,500$ ohms.

$$\text{From (4)} \quad L = \frac{26500}{2\pi f}$$

$$= \frac{26500}{6.28 \times 40000}$$

$$= 0.1055 \text{ henrys}$$

Translated into simple language, this means, in the case of the transformer previously referred to, that the reactance of the primary winding at 40,000 cycles may be reduced one-half by the addition, in series therewith, of an auxiliary inductance of .1055 henrys. Assuming that the high frequency voltage drop across the primary winding and

- auxiliary inductance in series remains unchanged, the high frequency currents passing through the transformer would be approximately doubled.
- 5 In most alternating current power distribution networks, the lines extending from the power stations or sub-stations each have a considerable number of transformers, some of which are much more efficient than others
- 10 in passing high frequency carrier currents. It has been found, however, that the majority of such transformers are capable of passing sufficient high frequency current to require no modification, that is to say, they do not
- 15 require the addition of auxiliary inductance. In fact, it is found that usually only a small percentage of the transformers require such treatment. As a rule it is not desirable to modify the high frequency impedance of a
- 20 deficient transformer so that it will pass the maximum possible amount of high frequency current, but only to such an extent that it will pass whatever is regarded as the necessary amount to effect satisfactory reception
- 25 at every subscriber's station served.
- The auxiliary inductance should, of course, be constructed to carry safely the power current which may be in the neighborhood of 5 amperes.
- 30 It is believed that in no case would the reactance of an auxiliary inductance, such as would be required, be sufficiently high to materially affect the power current.
- I claim:
- 35 1. A wired radio system comprising a power transmission line for the delivery of power and high frequency signaling energy to a plurality of subscriber stations, a power transformer at each of said subscriber stations, said power transformer having primary and secondary windings for delivery of said power to a load circuit, an auxiliary inductance device interposed in series with said
- 45 primary winding and connected across said transmission line, the combined impedance of said primary winding and said auxiliary inductance at the frequency of said signaling energy being less than the impedance of said primary winding alone at the same frequency
- 50 said auxiliary inductance being designed to pass said power to said load simultaneously with the delivery of said high frequency signaling energy to said load through said transformer.
2. A wired radio system comprising a transmission line for simultaneously conveying power and high frequency signaling energy to a plurality of subscriber stations, a plurality of power transformers each having primary and secondary windings, with the primary windings thereof connected in bridge to said line, a load circuit connected to said secondary windings including power consuming devices and wired radio receiving apparatus, and means for substantially 60 equalizing the supply of high frequency signaling energy to said wired radio receiving apparatus at each of said subscriber stations
- 65 said means comprising an inductance device connected in series with the primary winding of selected power transformers and in bridge to said line, said inductance devices each having such value that the combined impedance of associated primary windings and said inductance devices at the frequency of said signaling energy is substantially less than the impedance of said primary winding alone
- 70 at said frequency whereby said signaling energy may be transferred to said wired radio receiving apparatus at relatively large amplitude simultaneously with the supply of power to said load circuit through said transformers.
- 75 In testimony whereof I affix my signature.
